DELAWARE.

ADDING AND LISTING MACHINE.

Application filed December 31, 1920. Serial No. 434,242.

One of the objects of this invention is to provide an adding machine of relatively simple construction adapted to register items of English currency.

5 Another object is to provide a machine capable of being operated to add either English currency or decimal items.

Other objects of the invention will become apparent as the embodiment chosen for 10 illustration herein is described.

In the accompanying drawings, Figure 1 is a vertical longitudinal sectional view of a machine embodying the features of this invention, certain parts not directly related 15 to the invention being omitted. Fig. 1^a is a face view of some of the type bars. Fig. 2 is a view generally similar to Fig. 1, showing certain parts not illustrated in the last mentioned figure. Fig. 3 is a plan view of 20 the keyboard. Fig. 4 is a fragmental horizontal section. Fig. 5 is a fragmental elevational view taken from the side opposite to the handle side. Fig. 6 is a fragmental vertical section showing some of the stops 25 of the differential mechanism and a special hammer-actuating device. Fig. 7 is a front view of the hammer mechanism. Fig. 8 is a detail view of the devices that add and print the tens order of shillings when the 30 machine is set for English currency. In all of the foregoing views the machine is shown as set for adding and printing decimals. Fig. 8^a illustrates a specimen of work done upon the machine. Fig. 9 is a rear view 35 showing the lower portions of the type bars and the means for limiting movement of the pence type bar and the tens-shillings type bar. Fig. 10 shows the carrying mechanism associated with the tens-shillings type 40 bar, the parts being set for English currency. Fig. 11 is a rear view of a part of the mechanism shown in Fig. 10. Fig. 11^a is a plan view of a part of the carrying means. Fig. 12 is a plan view of the series 45 of adding pinions and part of the carrying mechanism. Fig. 13 is a plan section of a part of the setting-up mechanism, the parts being in the initial position. Fig. 14 is a view looking from the left-hand side of the 50 machine, showing the setting lever in the position for English currency. Fig. 15 is a similar view of the setting lever. Figs. 16, 17 and 18 illustrate portions of the setting up or keyboard mechanism.

I have herein shown the invention as embodied in a machine capable of dealing with both decimals and English currency, but it will be evident that certain features of the invention may be employed in a machine adapted to add or record English currency, 60 only.

For convenience in affording an understanding of the invention I shall describe the same as applied to or embodied in the ten-key adding and listing machine disclosed in Patent No. 1,198,487 granted September 19, 1916, to Rockford Milling Machine Company upon an application filed by Gustaf David Sundstrand, but I would have it understood that the present invention is 65 not limited to machines of the general character illustrated in said patent. Without, therefore, intending to limit the invention to machines of any particular type or character, I have herein illustrated a machine 70 comprising a platen 2 and a plurality of type bars. In the present instance there are ten type bars, but the number may be 75 greater or less.

The type bar A (Figs. 1, 4 and 9) at the 80 extreme right carries at its upper end a single type-carrying plunger 9' adapted to print a character which, when printed in red, denotes that the machine has been cleared, and, when printed in black, indicates that the item opposite which it appears has not been added. The type bar A 85 has no movement.

The second type bar from the right is marked A^x in Figs. 1^a, 2, 4 and 9 and carries twelve type plungers 9. The uppermost plunger is adapted to print a character (herein the letter D) to indicate that the machine is set to add and print decimals. The remaining plungers on the type-bar A^x 95 are adapted to print from one to eleven, respectively. The type-bar A^x is normally in position to print the character D.

The remaining type-bars are designated A¹, A², A³, A⁴, A⁵, A⁶, A⁷ and A⁸ in the 100 drawings, and each is provided with ten type-carrying plungers 9 adapted to print from naught to nine, respectively. The type-bars A¹ to A⁸, inclusive, are normally in position to print ciphers.

The means for vertically moving the bars A^x to A⁸, inclusive, from the normal or initial position to any other selected position 105

and back again may be of any preferred character, that herein shown being generally similar to the mechanism disclosed in the before-mentioned Patent No. 1,198,487 5 and identical with the mechanism shown in my copending application Serial No. 409-778, filed September 13, 1920 (now Patent No. 1,583,102, dated May 4, 1926). The type-bar-moving means need not, therefore, 10 be described herein further than to say that it comprises a handle 27 and connections to the type-bars including springs 14. When the operator pulls the handle 27 forward movement is yieldingly transmitted through 15 the springs 14 to such of the type bars A^x to A^s, inclusive, as are liberty to rise. When the operator releases the handle on the completion of the forward stroke, means of any ordinary or suitable character re- 20 turns the handle to the normal position shown in dotted lines in Fig. 1.

The means for limiting the extent to which the type-bars A^x to A^s, inclusive, may rise and thus to determine which numerals 25 shall be brought to the printing position may be of any preferred character. That herein shown is generally like the setting-up mechanism of Patent No. 1,198,487 and comprises a group of stops 42, each stop being 30 horizontally slidable in a forward and back direction in a stationary guide frame 43. When moved rearwardly from the position shown in Fig. 1 the stops are in the path of movement of devices carried by the type-bars A^x to A^s, inclusive, and thereby limit the upward movement of said bars. These 35 devices consist of arms 45 pivoted to the lower portions of the type-bars, and pins 46 having openings through which the arms 40 45 extend. The pins 46 are guided for vertical movement in a slide 47 which is mounted on a stationary guide rod 48 extending transversely of the machine. The guide rod 48 is so positioned with respect to the guide 45 frame 43 that the slide 47 is movable to carry the pins 46 from their normal or initial position at the left-hand side of the group of stops 42 into vertical alinement with the columns of stops. There are eleven 50 stops in each column.

When the machine is set for adding and printing decimals, those type-bars A^x to A^s, inclusive, which are not needed in accumulating or printing a given item are prevented from rising when the handle 27 is pulled forward by a detent plate 48^a (Fig. 13) guided to move in a horizontal plane, said plate being connected through a bar 48^b to a frame 48^c (Figs. 1 and 4). The frame 48^c is mounted to swing on the axis of a rod 5 and is normally impelled forward by springs (not herein shown, but disclosed in said Patent No. 1,198,487).

The means for projecting the stops 42 60 65 into the vertical path of movement of the pins 46 comprises a plurality of number keys 49 which are numbered from 0 to 9, as indicated in Fig. 3. The operating connections extending from the keys 49 may be of any desired nature, as, for example, that shown in my said Patent No. 1,583,102. The present drawings disclose operating connections like those illustrated and described in my said patent and hence need not be described herein in detail. Suffice it to say that each of the keys 49 is connected to an arm 54 of a lever pivoted on the axis 55 (Fig. 4.) A contractile spring 56 (Fig. 18) connected to the arm 57 of each of said levers serves to restore the corresponding key 49 to its normal position after a depression thereof. Two levers 58 and 58' (Figs. 4 and 17) are pivoted on the axis 55. To the arms 58 of said levers is fixed a vertical universal rod 59. A contractile spring 61 normally holds the universal rod 59 in contact with arms 54^a which are rigid with the arms 54.

A number key 49^a (Figs. 2 and 3) bearing the number 10 is attached to a stem 49^x which is mounted for vertical movement and which is impelled upwardly to its normal position by an expansion spring 50^x. A stud 51^x on the key-stem 49^x lies in contact with a cam surface 52^x on an arm 53^x which is pivoted on the center 53^a. The free end of the arm 53^x bears against the arm 54^x (Fig. 16) of a lever similar to the levers having the arms 54. A contractile spring 56^x (Fig. 16) connected to the arm 57^x serves to restore the arm 54^x and the arm 53^x to normal position. The key 49^a is used in adding and printing 10d.

A number key 49^b (Figs. 2 and 3) bearing the number 11 is affixed to a stem 49^y which is guided for approximately vertical movement. The lower end of the key-stem 49^y is pivoted to one arm of a lever 50^y which is pivoted on the center 53^a. To the other arm of the lever 50^y is connected a contractile spring 51^y that serves to impel the key 49^b upwardly to normal position, said position being determined by contact of a lug 52^y on the lever 50^y with a stop pin 53^y. On the lever 50^y is a stud 54^y (Fig. 17) that lies in front of a rod 55^y fixed to the levers 58 and 58'. It will be seen that when the key 49^b is depressed the frame composed of the levers 58 and 58' and the rods 55^y and 59 will be swung in one direction, and that when the key 49^b is released the spring 61 (Fig. 4) will restore said frame to normal position. The key 49^b is employed when adding and printing an item containing 11d.

As shown in Fig. 3, the number keys and the feature keys (i. e., the Non-print, Error, Repeat, Non-add and Total keys) are compactly grouped, the ten key 49^a being located

at the right of and adjacent to the nine key, and the eleven key 49^b being located directly behind the ten key.

A bracket 62 (Figs. 4 and 13) is pivoted 5 on the center indicated at 63, and carries a post 64 in which are slidably supported the rear ends of twelve push pins 65 (Fig. 2). The forward end of the uppermost push pin is pivoted to the lever 58 and consequently will be moved when the key 49^b is depressed. The next lower push pin is pivoted to the arm 54^x and therefore will be moved when the key 49^a is depressed. The remaining ten push pins are pivoted to the 15 arms 54 and hence will be moved when the respective keys 49 are depressed. The push pins are arranged in a vertical row or column and all except the uppermost push pin is adapted to push the stops 42 out of the 20 position shown in Fig. 1 and into the path of the upward movement of the pins 46.

The slide 47 is caused to move in unison with the bracket 62 by means of a pin 66 (Fig. 13) associated with said bracket and 25 lying within the bifurcation of a lug 67 on the slide. As the operator sets up an item of English money on the keyboard, the slide 47 and the bracket 62 are moved from one vertical row of stops 42 to the next adjacent 30 row as each number key 49, 49^a or 49^b is depressed and restored. The series of push pins 65 normally stands in front of the vertical row of stops which is farthest to the left, and is moved to successive vertical 35 rows of stops as the setting up of the item progresses. The series of pins 46 is moved from left to right, step by step. In adding and printing such an item as ten pounds, two shillings and ten pence, the item would 40 be printed as indicated in Fig. 8^a, where it will be seen that a space equivalent to that used for one numerical order is employed for pence, and that a space equivalent to that used for two numerical orders is reserved for shillings. Consequently, the 45 series of pins 46 is moved from left to right one step for each numerical order necessary in setting up pounds, two steps in setting up any quantity of shillings, and one step 50 in setting up any quantity of pence, thereby bringing the necessary number of pins 46 into vertical alinement with the stops 42 that have been set by the push pins 65.

In adding and printing decimal currency 55 the second typebar from the right (the type bar A^x) is used only to print the signal or distinguishing character "D" and is not employed in adding or recording digits. Therefore when adding and printing decimal currency it is necessary to impart to the slide 47 an extra movement or step in order to carry the pin 46 for the type-bar A^x out of alinement with any of the set stops 42 and to carry the pins 46 for the 60 type bars A¹ to A⁸ into vertical alinement

with the set stops. While this result may be attained by any suitable means, that herein shown comprises means for causing relative movement between the bracket 62 and the pin 66 (Figs. 1 and 13). Said 70 pin is fixed to the rear end of a lever 350 which is pivoted on a vertical axis 351 on the bracket 62. The pin 66 normally stands adjacent to a lug 352 on the bracket 62. The forward end of the lever 350 is held in contact with an adjusting member 353 by means of a torsion spring 354. The adjusting member is generally frusto-conical in form and is vertically slidable upon a stud 355. An arm 356 engaging a grooved portion of the adjusting member 353 is fixed upon a rock shaft 357. Rigidly attached to the shaft 357 is an arm 358 (Figs. 5 and 14) carrying a pin 359. A reciprocatory bar 360 (Figs. 5 and 14) is notched to provide a shoulder 361 adapted to engage the pin 359 and swing the arm 358 rearwardly to lower the adjusting member 353 and thus allow the torsion spring 354 to move the slide 47 one step to the right with relation 80 to the bracket 62. The notch alluded to also provides a shoulder 362 adapted to engage the pin 359 and push the arm 358 forwardly to raise the adjusting member 353 and thereby restore the slide 47 to normal 85 relation to the bracket 62. The forward end of the bar 360 is arranged to be held up in engagement with the pin 359 by a contractile spring 363 (Fig. 5) when decimals are being added or printed. The rear end 90 of the bar 360 is pivoted to a lever 76 fully described in my said Patent No. 1,583,102. During the early part of the forward stroke of the handle 27 the lever 76 is moved to draw the bar 360 rearwardly. During the 100 latter portion of the return stroke of the handle 27 said lever is moved to return the bar 360 to its initial or forward position.

When English currency is being added or printed the bar 360 is held down far 110 enough so that the shoulder 361 cannot engage the pin 359, but not too low to prevent the higher shoulder 362 from engaging said pin when necessary. The means for depressing the bar 360 comprises a setting lever 115 364 (Figs. 14 and 15) loosely fulcrumed on the rock shaft 357 and having a detachable finger piece 365 that extends up through a slot in the casing 274 (Fig. 1) of the machine at the left hand side of the keyboard. 120 The finger piece 365 has a split shank that fits over two headed studs 366 and 367. The lower portion of the bifurcation in the finger piece is enlarged to fit upon the stud 367, and the finger piece engages said stud 125 with sufficient spring pressure to hold the finger piece in place while allowing the finger piece to be pulled out when the casing 274 is to be removed.

The lever 364 carries a pin 368 that over- 130

lies the bar 360. When the finger piece 365 is shifted to the position shown in Fig. 14 (which is the position for adding or printing English money), the pin 368 holds the 5 bar 360 in such position that the shoulder 361 cannot move the arm 358. The lever 364 is yieldingly locked in either of its two 10 positions by a detent lever 369 (Fig. 15) which is pivoted at 370 and has a V-shaped tooth 371 that is pressed against a pin 372 on the lever 361 by a contractile spring 373. The pressure of the tooth 371 against the 15 pin 372 insures completion of movement of the lever 364 in either direction and holds 20 the lever in adjusted position. 374 and 375 are stop pins on the lever 364 which engage parts of the machine frame to limit oscillation of said lever.

A detent lever 376 (Fig. 14) pivoted at 25 370 has a notch to receive a pin 377 on the arm 358. 378 is a contractile spring that presses the detent lever 376 against the pin 377. Said detent lever serves to prevent accidental relative movement between the 30 slide 47 and the bracket 62 when the machine is set for adding or printing English currency.

The means whereby the handle 27 may cause the additional or extra relative movement between the group of stops 42 and the 35 group of pins 46 may be termed set-up-adjusting means.

In case the operator should shift the setting lever to the English currency position while 40 the handle 27 is in its forward position, the shoulder 362 on the bar 360 will return the adjusting member to its proper upper position during the return stroke of the handle.

A special stop is provided to hold down 45 the type bar A^x when adding or printing a decimal item or total, because the extra step imparted to the slide 47 by the torison spring 354 carries the pin 46 of said type bar out of register with any of the set stops 50 42. The special stop just referred to consists of a lug 379 (Fig. 9) formed upon a U-shape sheet metal member 380 which is virtually a lever pivoted to the framework by means of two screws 381. A headed 55 stud 382 limits movement of said lever in one direction. A spring 383 tends to hold the lever 380 in the position shown in full lines in Fig. 8, wherein the lug 379 lies in the path of upward movement of the tail 384 of the type bar A^x and thus prevents any character but the signal "D" from being printed by the type bar A^x .

The means for moving the lever 380 to 60 carry the lug 379 out of the path of movement of the type bar A^x when English money is to be added or printed comprises a rod 385 (Figs. 9 and 15) pivoted at its forward end to the setting lever 364 and slidably supported at its rear end to bear 65 against the lever 380. When the setting

lever 364 is moved to the position for adding or printing English currency, the rod 385 pushes the lower part of the lever 380 rearwardly far enough to place the lug 379 out of the way of the tail 384. The type 70 bar A^x is then free to rise to the extent permitted by a stop 42.

The slide 47 and the bracket 62 may be moved to the right by any preferred means, as, for example, a contractile spring 68, the 75 action of the spring being controlled by an escapement as described in said Patents Nos. 1,198,487 and 1,583,102, the escapement being operated by the uppermost push pin 65. As said push pin is pivoted to the lever 58 80 and said lever carries the universal rod 59, the top push pin 65 will be moved whenever any one of the keys 49, 49^a and 49^b is depressed.

The slide 48 and the bracket 62 may be 85 moved to the left into the initial position by any suitable means, as, for example, that disclosed in said Patents Nos. 1,198,487 and 1,583,102, the lever 76 forming a part of 90 said restoring means.

The means for driving the type-carrying plungers into contact with the inking ribbon may be of any preferred construction, that 95 herein shown being generally similar to the hammer mechanism of the well-known Sundstrand adding machine. The means for printing the Clear and Non-add signal is identical with that of the Sundstrand machine, and hence its construction and operation need not be here disclosed in detail. 100 It is sufficient to say that when the operator depresses the total key 177 or the non-add key 152 and pulls the handle 27, a bumper 101 is raised into position to transmit the blow of the hammer 100' to the typecarrying plunger 9', the ribbon also being operated so that the impression shall be made in one color opposite each non-added item and in another color opposite each final 105 total.

The hammer mechanism associated with each of the type-bars A^x to A^s , inclusive, 110 comprises a hammer 386 pivoted on the axis 387 and impelled by a contractile spring 388 to strike the type-carrying plunger that is positioned at the printing line. The hammers 386 are cocked and released by means 115 comprising two levers 389 (Fig. 7). The levers 389 are pivoted on the axis 387. A rock shaft or pivot 390 (Fig. 1) is mounted 120 in the levers 389. Pivoted on the shaft 390 is a frame 391 consisting of a piece of sheet metal bent to form two end pieces 392 and a connecting web 393, and two universal rods 394 and 395 are carried by the end pieces 392. The rod 394 is adapted to engage hooks 396 (Fig. 1) on the hammers 386 to draw forward or cock the hammers. A contractile spring 397 (Fig. 5) connected 125 to the rod 395 tends to swing the frame 391 130

- in the direction to hold the rod 394 in engagement with the hooks 396. Means similar to that disclosed in application Serial No. 110,823 filed July 24, 1916 (Patent No. 1,455,555 dated May 15, 1923), by Gustaf David Sundstrand is provided to tilt the frame 391 at the beginning of the return stroke of the handle 27 in the direction to disengage the rod 394 from the hooks 396.
- 5 Those hammers that correspond to the type bars which are not concerned in the printing of the given item or total are, however, restrained by latches 398 which are pivoted on the shaft 390 and are adapted to engage shoulders 399 (Fig. 5) on the hammers. The latches 398 are disengaged from those hammers which are needed to print the item or total by means of controlling levers 400 pivoted on the axis 401. The inner or rear 10 end of each lever 400 is adapted to enter a notch 402 (Figs. 1, 2 and 8) formed in its respective type bar. The other end of the lever 400 is normally held in contact with the rod 395 by a contractile spring 403.
- 15 In the forward portion of the lever 400 is formed a flaring notch or throatway 404 in which moves a stud 405 (Fig. 1) on the latch 398 located at the right of the lever. (The notch 404 in the extreme right-hand 20 lever 400 has no function, as no latch is associated with that lever.) The lower wall of the notch 404 constitutes a cam surface 406 (Fig. 5) which serves to insure that the latch 398 shall swing forward out of engagement with the shoulder 399 during the forward and downward movement of the frame 391 if gravity does not effect such disengagement.
- 25 When the handle 27 is pulled forward to cause the printing of an item or a total, the levers 389 swing down, thereby lowering the universal rod 395, the springs 403 drawing the forward ends of the levers 400 down as said rod descends. Before the forward 30 ends of the levers 400 have completed their downward movement they come in contact with the pivot shaft 390, which restrains said springs until said pivot shaft has passed below the forward ends of the levers, whereupon the forward ends of said levers complete their downward movement. As shown in Figs. 1 and 2, the inner ends of the levers 400 normally stand a little distance away from the type bars. The type bars which 35 are needed to print the item or total begin to rise before the inner ends of the associated levers 400 can enter the notches 402 of said type bars; consequently the inner ends of said levers stop against the forward 40 edges of the raised type bars, so that the continuing downward movement of the frame 391 causes the studs 405 of the latches 298 corresponding to the raised type bars to engage the cam surfaces 406 and be thereby 45 moved to release the corresponding hammers.
- The levers 400 which are associated with the type bars that do not participate in the printing operation engage the notches 402 of said type bars as soon as the descent 50 of the swinging frame 391 permits, the narrow portion of the throatways in said levers causing the corresponding latches 398 to remain in engagement with the hammers that correspond to the type bars that did not rise. 55 When the handle 27 commences its return stroke, means such as that disclosed in said Patent No. 1,455,555 causes the frame 391 to tilt upon its axis 390, thereby disengaging the rod 394 from the hooks 396 of all of the 60 hammers. Those hammers that correspond to the type bars that remained in the initial position are, however, restrained by the corresponding latches 398.
- 65 As hereinbefore stated, the type bars A' to A⁸, inclusive, are initially in position to print ciphers, and therefore when a cipher is to be printed there is no upward movement to be utilized in causing the corresponding hammers to print. Other means is accordingly provided to effect the release of the hammers that are to print ciphers. This means consists of a lug 407 (Figs. 5 and 7) 70 on each of the controlling levers 400 corresponding to the type bars A' to A⁸, inclusive, each of said lugs underlying a lug 408 on the lever 400 next to the right (with the exception that there is no lug on the lever 400 that corresponds to the type bar A⁸). When any lever 400 comes in contact 75 with a raised type bar, the lug 407 on said lever supports all the levers 400 at the right of said lug (with the exception just noted).
- 80 As previously stated, the machine herein disclosed, when printing decimals, is arranged to print the letter "D" opposite each item and total. Said distinguishing character is printed by the uppermost plunger 9 on the type bar A², hence there is no upward movement of said type bar to be 85 availed of to effect actuation of the corresponding hammer. I therefore provide special means to effect the desired result, which means will now be described.
- 90 A sheet-metal member 409 (Figs. 1, 2, 4, 5, 6 and 7), which is virtually a lever, is pivoted on the axis 410 and is provided with a finger 411 (Fig. 7) adapted to lie in the path of the downward movement of a stud 412 attached to the controlling lever 400 for 95 the type bar A². The lever 409 is connected through the medium of a link 413 (Fig. 5) to the stud 367 on the setting lever 364. Inasmuch as the movement of the lever 364 is greater than is needed for moving the 100 lever 409, the link 413 is formed with a loop 414 within which the stud 367 may move. A contractile spring 415 (Fig. 6)

tends to move the lever 409 in the direction to dispose the finger 411 out of the path of movement of the stud 412.

When the setting lever 364 is in the decimal position, and the handle 27 is pulled, the finger 411 holds the lever 400 for the type bar A^x in the same position that it would occupy if the inner end of said lever 400 were in engagement with a raised type bar; consequently the hammer for said type bar A^x will be caused to print the signal "D".

The lever 400 at the extreme right of the group of levers 400 serves only as a guide to hold the latch 398 of the hammer for the type bar A^x against lateral displacement. As a matter of convenience, said lever 400 and the one next to it may be rigidly secured together by means of the stud 412.

While various forms of adding mechanism may be employed, that herein shown comprises a series of adding pinions (see Fig. 12) rotatably mounted upon a shaft 126 which is carried by a frame 127 (Fig. 1) pivoted at 128. The pinions (of which there is one for each of the type-bars A^x to A^s , inclusive) are adapted to mesh with racks 129 formed in said type-bars. The pinion 125 x that meshes with the rack of the pence type-bar A^x has twelve teeth. The pinions 125 that mesh with the racks of the type-bars A^1 to A^s , inclusive, each have twenty teeth.

When an item is to be added the frame 127 is thrown forward to disengage the pinions from the racks before the type bars are raised; and said frame is swung rearwardly just before the type bars are moved downwardly. Addition therefore occurs in the downward stroke of the type bars, the extent of the rotation of the pinions depending, of course, upon the extent of movement of said bars. The frame 127 is swung to carry the pinions into and out of mesh with the racks by any suitable means, as, for example, that fully disclosed in the before-mentioned Patent No. 1,198,487.

While any preferred means for transferring or carrying from one numerical order to the next higher order may be used, that herein shown is generally similar to the carrying mechanism shown in said Patent No. 1,198,487. The carrying mechanism associated with the type bars A^s to A^1 , inclusive, is substantially identical with that illustrated and described in said patent.

The extent of the downward movement of the type bars A^1 to A^s , inclusive, is limited (except in the carrying operation) by contact of the shoulder 157 (Fig. 8) on said type bars with stop lugs 158. When an amount is to be carried from one order to the next higher order, the stop lug 158 for the type bar belonging to such higher order is withdrawn, thereby allowing that type bar to descend to the limit of its downward movement. The extent of such de-

scent is just sufficient to turn the adding pinion for that type bar through the distance of one tooth. Each stop lug is formed on a slide 159 which is guided for horizontal reciprocation. To each slide 159 is pivoted a dog 160 (Figs. 1 and 2) having a tooth 161 adapted to lie in front of a stationary locking plate 162. A spring 163 tends to hold the tooth 161 in engagement with the plate 162 and also tends to pull the dog 160 and the slide 159 rearwardly. When the tooth 161 is in engagement with the front edge of the plate 162, the stop lug 158 is in position to limit the downward movement of the corresponding type bar. When the tooth 161 is disengaged from the edge of the plate, the spring 163 pulls the dog and the slide back so that the stop lug 158 is out of the path of movement of the type bar.

In the case of the type bars A' and A^s , inclusive, the means for disengaging the tooth 161 from the plate 162 consists of two diametrically opposite lugs fixed to the pinion of the next lower order, as disclosed in said Patent No. 1,198,487. (In this embodiment of the invention, two lugs are provided because each pinion has twenty teeth.) When the amount accumulated on a pinion reaches 9, continued rotation of the pinion as the rack descends brings one of the aforesaid lugs against the end of the dog 160, thereby depressing the dog until the tooth 161 is below the front edge of the plate 162, whereupon the spring 163 pulls the dog and the slide 159 rearwardly until the lug 158 stops against the plate 162. The lug 158 is then out of the path of the rack of the next higher order, and the latter therefore moves down far enough to turn its intermeshing pinion through the distance of one tooth.

The carrying mechanism associated with the pence type bar A^x also is identical in substance with that disclosed in said Patent No. 1,198,487, the pinion 125 x (Fig. 2) having twelve teeth and having attached to one side a lug 164 adapted when the pinion makes a complete revolution to depress the dog 160 and thus release the unit-shilling type bar A^1 to downward movement equal to the distance of one tooth, thereby turning the pinion 125 for said type bar A^1 through the distance of one tooth, as explained in said Patent No. 1,198,487.

The carrying mechanism associated with the unit-shilling type bar A^1 for moving the tens-shilling type bar A^2 is like that described in said Patent No. 1,198,487.

Since there are twenty shillings in a pound sterling, the carrying mechanism for transmitting movement from the tens-shilling type bar A^2 to the unit-pound type bar A^3 operates whenever two tens have been accumulated on the pinion 125 x for the tens-

shilling type bar A². Said pinion (which has twenty teeth) has attached to one of its sides ten tripping lugs (see Fig. 10). The two diametrically opposite lugs are some-
 5 what longer than the others and are design-
 nated 164^a, the shorter ones being marked 164^b on the drawing. All of the lugs 164^a and 164^b are arranged to trip the transfer dog 160^a. When decimals are being accu-
 10 mulated the dog 160^a occupies a position out
 of reach of the lugs 164^b and within reach
 of the lugs 164^a, and hence is operated once
 for every ten teeth of the pinion 125^a.
 When English money is being registered the
 15 dog 160^a occupies a position farther for-
 ward so as to be operated by each of the
 lugs, and consequently is operated once for
 every two teeth of the tens-shilling pinion
 20 125^a. The means for determining the posi-
 tion of the dog 160^a comprises a rock shaft
 416 (Figs. 1 and 11), to one end of which
 is fixed an arm 417. Said arm is arranged
 to be swung forward by the setting lever
 25 364 through the medium of a link 418 (Fig.
 5). Inasmuch as the movement of the lever
 364 is greater than the arm 416 requires,
 the link 418 has a loop 419 at its rear end
 in which the headed stud 420 on the arm
 30 416 may slide. A contractile spring 421
 swings the arm 417 rearwardly when the
 setting lever 364 is swung back to the posi-
 tion for adding or printing English cur-
 35 rency. The shaft 416 is provided with an
 eccentric or crank portion 422 (Figs. 10 and
 11) which engages a slotted portion of a
 block 423 that rests on the plate 162. A
 leaf spring 424 engaging the rear portion
 40 of said block holds that end of the block
 down on the plate 162. On the forward
 end of the block 423 is a lug 425 that lies
 in a recess 426 (Fig. 11^a) in the front edge
 of the plate 162.

When English money is being added, the
 45 block 423 is in its down position, wherein
 the lug 425 fills the recess 426, the front
 edge of said lug being then flush with the
 front edge of the plate 162. The block 423
 is in the vertical plane of the transfer dog
 50 160^a. When the block 423 is down (as in
 Fig. 10) the tooth 161 of the dog 160^a en-
 gages the front edge of the lug 425, and
 therefore said dog is in position to be en-
 gaged by each of the lugs 164^a and 164^b,
 55 as a result of which the unit-pound type
 bar A² is given a carrying movement when-
 ever two tens have been accumulated on
 the pinion 125^a for the tens-shilling type
 bar A².

When decimals are to be added, the op-
 eration of the setting lever 364 causes the
 block 423 to be raised high enough so that
 the lug 425 is above the path of movement
 60 of the tooth 161, and consequently the spring
 163 holds the dog 160^a with its tooth 161
 in contact with the rear end wall of the

recess 426, in which position the front end
 of the dog 160^a is out of the orbit of the
 lugs 164^b but within reach of the lugs 164^a.
 Accordingly the type bar A² will be given
 a carrying movement whenever ten has been
 70 accumulated on the pinion 125^a for the type
 bar A². It will be seen that the lug 425
 and the rear end wall of the recess 426 con-
 stitutes two alined stops for the transfer
 dog 160^a.
 75
 After each carrying operation, the slide
 159 is restored to its normal (forward) po-
 sition by a universal rod 165 (Fig. 1) as ex-
 plained in said Sundstrand Patent No.
 1,198,487.
 80
 In the present embodiment of the inven-
 tion, a special stop is necessary to limit up-
 ward movement of the tens-shilling type bar
 A² when adding or printing an item of Eng-
 85 lish currency. The pinion 125^a is thrown
 out of mesh with said type bar before the
 type bar rises in printing an item; and con-
 sequently, in the absence of means to pre-
 vent such result, if through mistake twenty
 90 or more shillings were set up as such on
 the keyboard, the type bar A² would rise
 to the extent permitted by the correspond-
 ing stop 42 and hence incorrect results would
 be obtained. I therefore provide on the le-
 95 ver 360 (Fig. 9) a shoulder or projection
 427 which stands in the path of upward
 movement of a stud 428 on the tail 429 of
 the type bar A² (as shown in dotted lines
 in Fig. 8) when the setting lever 364 is in
 100 position for printing or adding English cur-
 rency and thus prevents the rise of the
 type bar A² above the position for printing
 "1".
 105

The mechanisms whereby a subtotal or a
 final total may be printed may be of any
 preferred character, as, for example, the
 mechanisms disclosed in Patent No. 1,198,487
 or in Patent No. 1,583,102.

It is believed that the operation of the
 machine will be clear from the foregoing
 description, particularly when reference is
 made to the sample of work shown in Fig.
 8^a. The fact that clear signals, subtotals
 and final totals are printed in a distinctive
 110 color has been indicated in Fig. 8^a by rep-
 resenting such signals and totals in dotted
 lines.

The setting lever 364 being in the decimal
 position, operation of the handle 27 will
 result in the printing of the character "D",
 as the finger 411 is in position to cause ac-
 tuation of the hammer for the type bar A²
 115 every time the handle is operated, whether
 in taking blank or spacing strokes or in
 printing an item, a subtotal or a final total.
 When the machine is clear, operation of the
 handle effects printing of the character "D"
 120 in the distinctive color, thus indicating that
 the machine is clear and set for decimal
 work.
 125
 130

In the example illustrated in Fig. 8^a, the final total "201" is accompanied by the Clear signal printed by the signal type bar A, as well as by the decimal signal.

- 5 The setting lever 364 being now shifted to its other position, an item of eleven pence may be printed and accumulated by depressing and releasing the key 49^b and operating the handle 27. An item of ten pence 10 may then be added and printed by operating the key 49^a and the handle 27. A blank stroke of the handle being first taken, the total of the two items may, if desired, be recorded by another operation of the handle. 15 An item of seventeen shillings may then be set up by operating the keys 49 marked "1", "7" and "0" in the order stated. When the handle is operated, the item of seventeen shillings will be printed. In this printing 20 operation, the pence type bar A^x of course remains in its initial position, but the uppermost type ("D") of said type carrier is not caused to print, because, as hereinbefore stated, there is no lug 408 on the controlling lever 400 for that type bar, and the finger 411 is out of the path of the stud 412.

The subtotal "189" (denoting 18s., 9d.) having been taken, an item of ten pounds, 25 two shillings, ten pence may be added and printed, the Naught key 49 being operated after setting up the pounds and before setting up the shillings.

A subtotal of the previous items, if desired, having been taken, an item of 9 pounds 30 may be set up by operating the keys 49 marked "9" and "0", the latter key being depressed three times.

The final total "20017" (denoting £20, 1s., 40 7d.) may now be recorded, the imprint being accompanied by the Clear signal.

Although I have described the present embodiment of the invention in considerable detail, it is to be understood that the construction and arrangement of the various mechanisms may be modified, that the timing and relative order of operation of the various mechanisms may be changed, and that certain features may be omitted without departing from the spirit and scope of the invention as set forth in the appended claims.

It will be apparent to those skilled in the art that the rigid connection herein shown 55 between the type carriers and their respective racks or actuators is not of the essence of the present invention, and that other well known arrangements of the type carriers and racks or actuators may be employed.

Certain features of the transfer mechanism are claimed in my divisional application Serial No. 71,851, filed November 27, 1925.

I claim as my invention:

65 1. An adding machine adapted to print in

decimal and English currency notation including a type-carrying member provided with twelve type adapted, respectively, to print a single character to indicate a decimal item, and the numbers 1 to 11, inclusive, 70 in the order stated for use in printing in English currency notation.

2. An adding machine adapted to print in decimal and English currency notation including a type-carrying member provided with twelve type adapted, respectively, to print a signal to indicate a decimal item, and the numbers 1 to 11, inclusive, 75 in the order stated, for use in printing in English currency notation, the signal type being normally at the printing line, and means to move said member to position a selected number-type at the printing line. 80

3. An adding machine adapted to print in decimal and English currency notation 85 including a type-carrying member provided with twelve type adapted, respectively, to print a signal to indicate a decimal item, and the numbers 1 to 11, inclusive, 90 in the order stated, for use in printing in English currency notation, the signal type being normally at the printing line, means to move said member to position a selected number-type at the printing line, and means to disable said moving means when printing a 95 decimal item.

4. An adding machine adapted to print in decimal and English currency notation, including a type-carrying member provided with twelve type adapted to print different characters, means to move said member to position a selected type at the printing line when printing an English currency item, and means to prevent said moving means from moving the uppermost type above the printing line when printing a decimal item. 100

5. An adding machine adapted to print in decimal and English currency notation, including a type-carrying member provided with twelve type adapted to print different characters, means to move said member to position a selected type at the printing line when printing an English currency item, a stop to prevent said moving means from moving the uppermost type above the printing line when printing a decimal item, and manipulative means for adjusting said stop. 110

6. A machine for adding both decimals and English currency, said machine including a type-carrying member provided with a plurality of type, means to move said member to position a selected type at the printing line when dealing with English currency, and means to prevent movement of said member when dealing with decimals. 120

7. A machine for adding both decimals and English currency, said machine including a type-carrying member provided with ten type adapted to print from 0 to 9, inclusive, in the order stated, means to move 125

said member to position any selected type at the printing line when dealing with decimals, and means to prevent movement of said member to position any type above

5 "1" at the printing line when dealing with English currency.

8. An adding machine including a type-carrying member provided with ten type adapted to print from 0 to 9, inclusive, in the 10 order stated, means to move said member to position a selected type at the printing line, and means to prevent such movement beyond the position for printing "1," said preventing means including a device operable 15 by the hand of the operator.

9. An adding machine including a type-carrying member provided with a plurality of type, means to move said member to position a selected type at the printing line, and 20 means to prevent such movement beyond a certain position, said preventing means including a device adapted to be set by the hand of the operator.

10. An adding machine having printing 25 mechanism including a plurality of hammers for printing numbers and a special hammer for printing a sign, a handle, and connections between the handle and the hammers for actuating said hammers, and manipulative means for actuating the special hammer during a blank stroke of the handle.

11. An adding machine having printing mechanism including a plurality of hammers 30 for printing numbers and a special hammer for printing a sign, a handle, a key-board, means controlled through the key-board for causing actuation of selected number-printing hammers upon operation of the handle, and means independent of the key-board 35 for causing actuation of the special hammer during a stroke of the handle.

12. A machine having a supporting 40 framework, a group of stops and a group of parts to be controlled by said stops, one of said groups being movable transversely of the framework, a swinging bracket, a lever pivoted on said bracket and connected at one end to the last-mentioned group, an adjusting member having an inclined surface 45 and mounted to move on the axis of said bracket, a spring holding the other end of said lever in contact with said inclined surface, a handle for operating the machine, means automatically actuated in the reciprocation of the handle to reciprocate said 50 adjusting member, and manually operable means to prevent said automatically actuated means from moving said adjusting member in a certain direction.

13. An adding machine having stops, 55 parts to be controlled by said stops, a key-board and connections for causing relative movement between said stops and parts, a main operating handle, and means actuated

65 by the handle during the initial part of the movement of the latter for causing further relative movement between said stops and parts.

14. An adding machine having a group of 70 stops, a group of parts to be controlled by said stops, a key-board and connections for causing relative movement between said groups, a main operating handle, and means actuated by the handle during the initial 75 part of the movement of the latter for causing further relative movement between said groups.

15. An adding machine having a supporting 80 framework, a group of stops and a group of parts to be controlled by said stops, one of said groups being movable transversely of the framework, a key-board and connections for causing transverse movement of the last-mentioned group in a certain direction, a main operating handle, and means 85 actuated by the handle for causing further transverse movement of said group in said direction.

16. An adding machine having a supporting 90 framework, a group of stops and a group of parts to be controlled by said stops, one of said groups being movable transversely of the framework, number keys and connections for causing transverse movement of the last-mentioned group in a 95 certain direction, and other means for causing further transverse movement of said group in said direction.

17. In an adding machine, a group of 100 stops and a group of parts to be controlled by said stops, one of said groups having movement in a certain direction relative to the other group, a main operating handle, and means actuated by the handle for causing further movement of said movable 105 group in said direction.

18. A machine having a supporting framework, a group of stops and a group of parts to be controlled by said stops, a swinging 110 bracket for moving one of said groups transversely of the framework, a lever pivoted on said bracket and connected at one end to the last-mentioned group, means to adjust said lever relative to the bracket, a handle for operating the machine, and means automatically actuated in the reciprocation of the handle to operate said adjusting means.

19. An adding machine having set-up-adjusting means, transfer-adjusting means, 115 rack-movement limiting means, and hammer-controlling means, and a single device controlling all of said means.

20. An adding machine having set-up-adjusting means, transfer-adjusting means, 120 rack-movement limiting means, and hammer-controlling means, and a single manipulative member controlling all of said means.

21. An adding machine having, in combination, a plurality of actuators, each having a movable stop portion, a stationary group of stops, means for setting the stops, means for moving said movable stop portions in a certain direction into operative alignment with the set stops, and other means for causing a further movement of said stop portions in said direction. 70
- 10 22. A machine having a supporting framework, a group of stops and a group of parts to be controlled by said stops, a swinging bracket for moving one of said groups transversely of the framework, a lever pivoted on said bracket and connected at one end to the last-mentioned group, and means to adjust said lever relative to the bracket. 75
- 15 23. A machine having a supporting framework, a group of stops and a group of parts to be controlled by said stops, a swinging bracket for moving one of said groups transversely of the framework, and an adjustable connection between said bracket and the last-mentioned group. 80
- 20 24. An adding machine having a supporting framework, a group of stops and a group of parts to be controlled by said stops, means to move one of said groups transversely of the framework, and an adjustable connection between said moving means and the last-mentioned group. 85
- 25 25. An adding and printing machine for working in decimal and English currency notations having, in combination, a group of vertically reciprocatory type bars, one of which is used for printing a decimal sign and pence, and another of which is used for printing tens of decimals and tens of 90 shillings, a lever pivoted adjacent to the type bars, said lever having a portion adapted to prevent movement of the first-mentioned type bar, and another portion to limit movement of the second-mentioned type bar, and means for moving said part into position to control either of said type bars. 95
- 30 26. An adding and printing machine for working in decimal and English currency notations having, in combination, a group of vertically reciprocatory type bars, one of which is used for printing a decimal sign and pence, and another of which is used for printing tens of decimals and tens of shillings, and mechanism to prevent movement 100 of the first-mentioned type bar and to limit movement of the second-mentioned type bar. 105
- 35 27. An adding and printing machine having, in combination, a keyboard, a printing mechanism including a plurality of hammers for printing numbers and a special hammer for printing a sign, a handle for operating the machine, connections between the handle and the hammers for actuating said hammers to print numbers, and means for actuating the special hammer during a blank stroke of the handle comprising a lever arranged to operate said special hammer, a manually operable lever adjacent to the keyboard and connections between said levers. 110
- 40 28. An adding and printing machine having, in combination, printing mechanism including a plurality of hammers for printing numbers, and a special hammer for printing a sign, a handle, a keyboard, means controlled through the keyboard for causing actuation of selected number-printing hammers upon operation of the handle, and means including a manually shiftable lever 115
- 45 29. An adding and printing machine having, in combination, a group of vertically reciprocatory type bars, one of which is used for printing a decimal sign and pence, and another of which is used for printing tens of decimals and tens of shillings, a part having a portion adapted to prevent movement of the first-mentioned type bar and another portion to limit movement of the second-mentioned type bar, and means for moving said part into position to control either of said type bars. 120
- 50 30. An adding and printing machine having, in combination, a group of vertically reciprocatory type bars, one of which is used for printing a decimal sign and pence, and another of which is used for printing tens of decimals and tens of shillings, and mechanism to prevent movement of the first-mentioned type bar and to limit movement of the second-mentioned type bar. 125
- 55 31. An adding and printing machine having, in combination, a keyboard, a printing mechanism including a plurality of hammers for printing numbers and a special hammer for printing a sign, a handle for operating the machine, connections between the handle and the hammers for actuating said hammers to print numbers, and means for actuating the special hammer during a blank stroke of the handle comprising a lever arranged to operate said special hammer, a manually operable lever adjacent to the keyboard and connections between said levers. 130
- 60 32. An adding and printing machine having, in combination, printing mechanism including a plurality of hammers for printing numbers, and a special hammer for printing a sign, a handle, a keyboard, means controlled through the keyboard for causing actuation of selected number-printing hammers upon operation of the handle, and means including a manually shiftable lever

mounted adjacent to the keyboard for causing actuation of said special hammer during a blank stroke of the hammer.

33. An adding and printing machine having, in combination, a keyboard, a printing mechanism including a plurality of hammers for printing numbers, and a special hammer for printing a sign, a handle for operating the machine, connections between

the handle and the hammers for actuating 10 said hammers to print numbers, and means for actuating the special hammer during a blank stroke of the handle including a manually operable member adjacent to the keyboard.

In testimony whereof, I have hereunto set my hand.

OSCAR J. SUNDSTRAND.
